CLAIM

The ornamental design for a combination irradiation device and hybridizer, as shown.

DESCRIPTION

FIG. 1 is a generally perspective view of a combination irradiation device and hybridizer showing my new design;

FIG. 2 is a front view thereof;

FIG. 3 is a side view thereof, the opposite side being a mirror image;

FIG. 4 is a top plan view thereof;

FIG. 5 is a rear view thereof; and,

FIG. 6 is a bottom plan view thereof.
